CLAIM

The ornamental design for an amino acid analyzer, as shown in the Figures.

DESCRIPTION

FIG. 1 is a front elevational view of an amino acid analyzer showing our new design;

FIG. 2 is a top view of the amino acid analyzer shown in FIG. 1;

FIG. 3 is one end view of the amino acid analyzer shown in FIG. 1; and

FIG. 4 is the other end view of the amino acid analyzer shown in FIG. 1.

FIG. 2

FIG. 1

FIG. 4

FIG. 3
